UNITED STATES PATENT OFFICE.

AUGUST J. MESSLER, OF BUFFALO, NEW YORK.

DESIGN FOR A BADGE OR SIMILAR ARTICLE.

SPECIFICATION forming part of Design No. 34,916, dated August 13, 1901.

Application filed July 2, 1901. Serial No. 66,915. Term of patent 3½ years.

To all whom it may concern:

Be it known that I, AUGUST J. MESSLER, a citizen of the United States, residing at Buffalo, in the county of Erie and State of New York, have invented and produced a new and original Design for a Badge or Similar Article, of which the following is a specification, reference being had to the accompanying drawings, forming a part thereof.

10 This invention relates to a design for a badge or similar article.

In the accompanying drawings, Figure 1 is a front elevational view of a badge or similar article, illustrating my design. Fig. 2 is an 15 edge view thereof.

As shown in the drawings, the leading or essential feature of the design comprises, as indicated at A, the representation of the front portion of the head or the face of a buffalo, 20 having indicated on the forehead thereof, as at B, the Western Hemisphere or the con-

tinents of North and South America. The head or face illustrated is of substantially oval outline in front or face view and shows the full front face of the buffalo, the front side 25 being convexed. The Western Hemisphere indicated is located in the central upper part of the face or forehead between and depending somewhat below the curved inwardly-turned horns C. The lower end of South 30 America extends downward to a point approximately centrally between the eyes.

What I claim is—

The design for a badge or similar article, substantially as shown and described. 35

Witness my hand this 28th day of June, 1901.

AUGUST J. MESSLER.
